UNITED STATES PATENT OFFICE.

ERNEST A. WALKER, OF NEWARK, NEW JERSEY, ASSIGNOR TO WILLIAM GOLDBERG
AND ABE GOLDBERG, BOTH OF NEWARK, NEW JERSEY, TRADING AS THE G & G
FIXTURE CO., A COPARTNERSHIP.

DESIGN FOR A SCROLL ARM FOR LIGHTING FIXTURES.

Application filed March 17, 1925. Serial No. 12,746. Term of patent 7 years.

To all whom it may concern:

Be it known that I, ERNEST A. WALKER, a citizen of the United States, residing at 762 Summer Avenue, Newark, in the county of Essex and State of New Jersey, have invented a new, original, and ornamental Design for a Scroll Arm for Lighting Fixtures, of which the following is a specification, reference being had to the accompanying drawing, forming part thereof.

Fig. 1 is a side view of a scroll arm for lighting fixtures, showing my new design. Fig. 2 is a front view thereof.

I claim:

The ornamental design for a scroll arm for lighting fixtures, as shown.

In witness whereof, I hereunto subscribe my name, as attested by the two subscribing witnesses.

ERNEST A. WALKER.

Witnesses:

ABE GOLDBERG,
L. E. FISCHER.
